UNITED STATES PATENT OFFICE.

HERMANN ROOST, OF LE LOCLE, SWITZERLAND.

WINDING AND HAND-SETTING MECHANISM FOR WATCHES AND THE LIKE.

No. 927,877.

Specification of Letters Patent.

Patented July 13, 1909.

Application filed July 28, 1908. Serial No. 445,827.

To all whom it may concern:

Be it known that I, HERMANN ROOST, of Le Locle, Canton of Neuchâtel, Switzerland, have invented a new and useful Improvement in Winding and Hand-Setting Mechanism for Watches and the Like, of which the following is a full, clear, and exact description.

The accompanying drawing shows by way of example two embodiments of the invention.

Figure 1 shows one embodiment in plan partly in section. Fig. 2 is a plan view on the opposite side to Fig. 1. Fig. 3 is a cross section on the broken line A—B—C of Fig. 1. Fig. 4 shows in plan partly in section, a second constructional form of the mechanism forming the object of the invention. Fig. 5 is a cross section on the line D—E of Fig. 4. Fig. 6 shows a modified construction of a detail, in plan.

Upon the square on the false rod *a*, which is loosely fitted into the plate *b*, the sliding pinion *c* is capable of displacement in the longitudinal direction; this pinion may either be brought into engagement with the pinion *d* of the winding mechanism for winding, or with an idle pinion, not shown in the drawing, for setting the hands.

The winding pinion *d* rotates freely on the journal *e* on the winding rod *a* which is bored throughout its entire length and in which the winding rod *f* is able to move in the longitudinal direction only. This rod acts at its extremity opposite to the pendant of the watch, upon a small cylindrical rod *g*, the end *h* of which rests upon the extremity of a lever *i*, pivoted at *k* and having upon it a toothed segment *l* meshing with a similarly toothed segment *m* on a disk *n* which is pivoted at *o*. Upon this disk *n* (and likewise pivoted at *o*) there is arranged a piece *p* provided with a finger *q* engaged in the groove *r* of the sliding pinion. To the oscillating disk *n* there is fixed a pin *s* passing into a hole *t* through the plate *b*, its extremity opposite the said hole being engaged between a part *u* of the disk *p* and the end of a circular spring *v* formed in one piece with the disk *p*.

Beneath the rocking lever *i* there is arranged in a groove *w* in the plate a circular spring *y*, one of the ends of which is attached to the plate *b* while the other ex-

tremity is attached to the lever *i*. This spring *y* has a constant tendency to keep together the end of the lever *i* and the end *h* of the rod *g* and also, by the action of the pin *s* against the part *u* of the disk *p*, to retain the sliding pinion *c* in its lower position (Figs. 1 and 3) for setting the hands.

Beneath the plate *b* there is formed a rectilinear groove *z*, as shown in Fig. 2, into which a rod *l* rectangular in section, ending toward the interior of the movement in a bevel *2* and outside of the movement in a hook *3* to withdraw said rod, can be introduced. The groove *z* passes through the hole *t* and by introducing the rod *l* the latter displaces to one side the pin *s* which, acting against the end of the spring *v*, holds the sliding pinion *c* in engagement with the winding pinion *d*, in order that the watch movement may be wound when out of its case. The rod *l* has to be withdrawn when the movement is to be placed in the watch case. The winding rod *f*, in this embodiment of the invention (Figs. 1 to 3), is a part of the spring device in the pendant of the case. This is a known device which insures the stability of the rod in both its positions, *i. e.* when pushed in and drawn out.

When the winding rod *f* is drawn out, the parts of the mechanism occupy the position represented in Figs. 1 and 3; that is to say, under the influence of the spring *y* the finger *q* of the part *p* holds the sliding pinion *c* in the position in which it meshes with the idle wheel of the hand setting mechanism.

By pressing the rod *f*, the lever *i* is caused to traverse a fraction of a revolution, in displacing the spring *y* and causes the rotation of the piece *n* in the opposite direction (likewise through a fraction of a revolution). The pin *s* in pressing against the end of the spring *v* in the direction indicated by the arrow 4 (Fig. 1) produces the rotation of the part *p*, the finger *q* of which presses the sliding pinion *c* against the winding pinion *d* for winding the movement. In this position not only does the spring *v* insure contact between the ratchet teeth 5 and 6 of the pinions *c* and *d* respectively while enabling the engagement and disengagement of these pinions, but this spring *v* also permits of a supplementary travel of the rod *f* for the operation of the secret opening spring for the watch casing, as by pressing the rod *f*

farther home the only effect produced is to displace the spring *v*.

In the construction illustrated in Fig. 4, the false rod is dispensed with, and it is the winding rod 7 itself which operates the lever *i*, its end 8 resting upon this lever. The sliding pinion *c*, like the winding pinion, is arranged directly upon the winding rod 7 and the stability of the "pulled" and "pushed" positions of this rod is insured, not by means of the known arrangement of a spring catch in the pendant, but by a pivoted spring bolt 9 (Fig. 5) constantly resting against the rod 7 and assuming a position on one side or the other of a projection 10 on this rod, according as the said rod is pushed or pulled. The rod 7 is prevented from leaving the movement completely by a bearing 11 on this rod, against which the spring bolt strikes when the said rod is pulled out to its fullest extent (Figs. 4 and 5). The operation of this form of mechanism is similar to that described above.

To enable the winding rod to be withdrawn from the movement readily, and for facilitating the placing of the movement in its case and withdrawing it therefrom, a screw 12 comprising a frusto-conical part 13 is screwed into the plate *b*. This part 13 is placed beneath an inclined surface 14, on the spring bolt 9 in such a manner that by unscrewing this screw slightly its part 13 lifts the spring bolt pivoting at 15 and releases the rod 7 which can be withdrawn from the movement. The part carrying the finger driving the sliding pinion (which part is connected by a spring with the toothed member meshing with the toothed lever operated by the winding rod) may be in one piece with the said toothed member, as shown in Fig. 6. In this construction, the finger 16 engaged in the groove *r* in the sliding pinion *c* for displacing it longitudinally, is constituted by the end of a spring 17 shaped as the arc of a circle, fixed to the pivoted part 18 meshing, by means of its teeth *m*, with the teeth *l* on the lever *i*. The operation of this modified form of mechanism is identical with that described above; the spring 17 performing absolutely the same function as the spring *v* in the constructional forms represented in Figs. 1 to 4.

The form and dimensions of the parts described may vary, of course, without departing from the invention.

Having now described my invention I claim as new and wish to secure by Letters Patent:—

1. In winding and hand-setting mechanism for watches, the combination of the winding rod, the sliding pinion, a rocking lever operated by the winding-rod, an inelastic disk oscillated by said rocking lever and carrying a pin, and a second disk having a common pivot with the first and formed

with a part to engage and operate the sliding pinion and with a spring abutting against said pin.

2. In winding and hand-setting mechanism for watches, the combination with the winding rod and the sliding pinion, and the mechanism to shift said pinion comprising a disk connected therewith and provided with a pin, of a sliding rod movable in a groove and adapted to engage and displace said pin.

3. In winding and hand-setting mechanism for watches, the combination with the sliding pinion, and the mechanism to shift said pinion comprising a disk connected therewith and provided with a pin, of a rod slideable in a groove in the movement-plate and having a beveled end by which said pin is shifted laterally.

4. In winding and hand-setting mechanism for watches, the combination with a winding-rod having a projection, of a pivoted spring-bolt adapted to be held by its spring action against the rod at either side of said projection, and a screw having an inclined surface by means of which said spring-bolt may be raised on its pivot.

5. In a winding and hand-setting mechanism for watches, the combination, with the plate, the winding rod and the annularly-grooved sliding pinion, of a rocking lever abutting the inner end of the winding rod, a disk pivoted to the plate and engaging the rocking lever, a second disk pivoted to the plate and having a shoulder and a circular spring and carrying a finger engaging in the annular groove of the sliding pinion, and a pin carried by the first disk and engaging between the shoulder and the end of the circular spring.

6. In winding and hand-setting mechanism for watches, the combination, with the plate, the winding rod and the annularly-grooved sliding pinion, of a toothed rocking lever abutting the inner end of the winding rod, a toothed disk meshing with the rocking lever and movable on a pivot-pin carried by the plate, a second disk movable on the said pivot-pin and having a shoulder, a circular spring and carrying a finger engaging in the annular groove of the sliding pinion, and a pin carried by the toothed disk and engaging between the shoulder and the end of the circular spring.

7. In winding and hand-setting mechanism for watches, the combination, with the plate, winding rod and the annularly-grooved sliding pinion, of a toothed rocking lever pivoted on the plate and abutting against the inner end of the winding rod, a spring pressing the rocking lever to hold it against the winding rod, a toothed disk meshing with the rocking lever and movable on a pivot point carried by the plate, a second disk movable on the said pivot point

and having a shoulder and a circular spring
and carrying a finger engaging in the an-
nular groove of the sliding pinion, a pin car-
ried by the toothed disk and engaging be-
5 tween said shoulder and the end of the
circular spring, and additional means for
engaging and moving the last-named pin.

In testimony, that I claim the foregoing as
my invention, I have signed my name in
presence of two subscribing witnesses.

HERMANN ROOST.
